(57)

CLAIM

The ornamental design for a decanter and base, as shown and described.

DESCRIPTION

FIG. 1 is a top plan view of a decanter and base showing my new design;

FIG. 2 is a front perspective view thereof;

FIG. 3 is a rear perspective view thereof;

FIG. 4 is a left side perspective view thereof;

FIG. 5 is a right side perspective view thereof;

FIG. 6 is an environmental front view thereof;

FIG. 7 is a right side perspective thereof;

FIG. 8 is a left side perspective view thereof;

FIG. 9 is a top plan view of the decanter and base with the decanter removed for ease of illustration;

FIG. 10 is a side perspective view thereof;

FIG. 11 is a rear perspective view thereof;

FIG. 12 is a left side perspective view thereof;

FIG. 13 is a right side perspective view thereof;

FIG. 14 is a top perspective view thereof; and,

FIG. 15 is another top perspective view thereof.

The broken lines in the drawings depict portions of the decanter and base that form no part of the claimed design.
